Primary Examiner—Gary D. Watson

(74) Attorney, Agent, or Firm—Luce, Forward, Hamilton & Scripps LLP

(57) CLAIM

The ornamental design for a seat, as shown and described.

DESCRIPTION

FIG. 1 is a front perspective view of one embodiment of my new seat design in the form of a sofa;

FIG. 2 is a close-up view of a portion of the embodiment of FIG. 1;

FIG. 3 is a front elevation view of the embodiment of FIG. 1;

FIG. 4 is a left, side elevation view of the embodiment of FIG. 1, with the right side elevational view being a mirror image thereof;

FIG. 5 is a rear elevation view of the embodiment of FIG. 1;

FIG. 6 is a front perspective view of a second embodiment of my new seat design in the form of a chair;

FIG. 7 is a front elevation view of the embodiment of FIG. 5; and,

FIG. 8 is a rear elevation view of the embodiment of FIG. 5.

The side elevation views of FIGS. 6, 7 and 8 are like that shown in FIG. 4.

The broken line disclosure is for illustrative purposes only and forms no part of the claimed design.

1 Claim, 4 Drawing Sheets
